United States Patent Office

Des. 221,824
Patented Sept. 14, 1971

221,824

HOLDER FOR AN ELECTRIC TOOTHBRUSH OR SIMILAR DEVICE

William J. Cook, Trumbull, Conn., assignor to
General Electric Company

Filed June 24, 1970, Ser. No. 23,639

Term of patent 14 years

Int. Cl. D4—02

U.S. Cl. D4—16

Fig. 1.

Fig. 2.

Fig. 3.

Fig. 4.

Fig. 5.

Fig. 6.

Fig. 7.

FIG. 1 is a perspective view of a holder for an electric toothbrush embodying my new design;

FIG. 2 is a front elevational view;

FIG. 3 is a top plan view;

FIG. 4 is a rear elevational view;

FIG. 5 is a bottom plan view;

FIG. 6 is a right side elevational view; and

FIG. 7 is a left side elevational view.

I claim:

The ornamental design for a holder for an electric toothbrush or similar device, substantially as shown.
